To all whom it may concern:

Be it known that I, ALLMON FORDYCE, a citizen
of the United States, residing at New York, coun-
ty of New York, State of New York, have invented
a new, original, and ornamental Design for a
Vacuum Cleaner Casing, of which the following
is a specification, reference being had to the
accompanying drawing, forming a part thereof.

The figure is a perspective view of a vacuum
cleaner casing showing the new design.

I claim:

The ornamental design for a vacuum cleaner
casing, as shown.

In witness whereof, I have hereunto set my
hand this 31st day of August, 1933.

ALLMON FORDYCE,
